UNDERGROUND TUNNEL CONSTRUCTION

Charles D. Jacobs, Pikeville, Ky.

Application April 25, 1942, Serial No. 440,553

21 Claims.

(Cl. 61—42)

This invention relates to improvements in underground tunnel construction and is particularly concerned with the formation of arches or other roofs.

A major object of the invention is to control the strata above the tunnel roof and in this connection contemplates construction of the tunnel roof in sections with only a small area above the roof exposed at any one time so that each section of the roof arch is keyed to the side walls and is self-supporting.

A further object of the invention is to utilize the rock or other earthy material beneath the tunnel roof to support the same until the roof is completed, whereupon the underlying balance of the tunnel is excavated to the desired size of the structure.

A further object of the invention is to afford protection for the green concrete forming the tunnel roof so as to prevent damage to the concrete when shooting out or blasting the underlying material to complete the tunnel.

Another object of the invention is to provide a novel method of constructing blind tunnels, i.e., tunnels dug or blasted in the side of an embankment or working face and having the innermost end thereof closed.

The invention in general involves a simple method of modified long-wall mining and back filling with reinforced concrete.

While the invention is applicable to the construction of tunnels or underground structures in general, the principles thereof have been found to be particularly applicable and are herein illustrated and described in connection with the formation of an underground dry dock in which ships may be housed, protected from damage by bombs and invisible from overhead, together with materials necessary to repair and upkeep of the ships. This particular type of structure is also ideally suited for airplane hangars, oil and munitions storage, as well as for protection of humans.

Referring to the accompanying drawings wherein a particular embodiment of the invention as aforesaid has been selected for exemplification:

Fig. 1 is a vertical section of a completed dry dock or tunnel;

Fig. 2 is a plan view of Fig. 1 partly broken away to show the tunnel structure;

Fig. 3 is an end view of Fig. 1 looking into the tunnel structure;

Fig. 4 is a broken substantially horizontal section taken through the roof area during the proc-

ess of its construction and looking downwardly; Fig. 5 is a side elevational view of the left hand end of Fig. 4 showing the temporary waste chutes for the discharge of material delivered thereto from the belt conveyors disposed in the longitudinal passageways;

Fig. 6 is a fragmentary view similar to Fig. 4 but showing a portion of the roof completed;

Fig. 7 is a sectional view taken on the line 7—7 of Fig. 4;

Fig. 8 is a sectional view taken on the line 8—8 of Fig. 6 before excavation of the material underlying the roof and illustrating the provision of collapsible means between the roof and underlying support; and

Fig. 9 is a sectional view taken on the line 9—9 of Fig. 8.

After the location for the structure has been determined and prospected by core drilling to ascertain definitely that the local structure has mechanical strength to support the arch, a plurality of spaced passageways A, B and C are driven inwardly from a working face or embankment for the full length of the dry dock or other tunnel structure. As the passageways A, B and C are driven conveyor belts 10 may be placed therein and at the inner end cross cuts or cross passageways indicated at D are driven at right angles to connect the passageways A and B and B and C. Chain conveyors 11 are then placed in the passageways D near the out-by rib to deliver rock to the belt conveyors in the passageways A and C as mined. Temporary waste chutes indicated at 12 are constructed convenient to the open ends of the passageways A, B and C as best illustrated in Fig. 5.

A modified long-wall face has now been developed. Excavation of the remaining roof area for the construction of the roof arch sections may then be initiated by drilling and shooting on the out-by rib as indicated at the right hand end of Fig. 4. For ordinary purposes I have found that the various arch sections may be conveniently formed in widths of 8 to 10 feet and the broken lines in Fig. 4 extending transversely of the tunnel indicate the positioning of successive arch sections working toward the entrance to the structure.

Fig. 6 illustrates the roof arch as partially completed; the completed sections being indicated at 14. It will be noted that as the various concrete sections are completed, the conveyor belts 10 in the passageways A, B and C are shortened in order to operate upon the material being excavated from the next succeeding section area. In

Fig. 6 a form indicated at 16 has been placed for the pouring of concrete admitted by the conveyor belt 10 in the passageway B for the formation of the next succeeding arch section adjoining the completed sections 14.

The invention contemplates that a small area of the tunnel structure is exposed at any one time. While the roof area as indicated in Fig. 6 may be excavated for the width of several roof sections for convenience of operation, it will be apparent that further excavation proceeds only as each segment of the concrete arch is formed and becomes keyed to the side walls and self-supporting. In this manner no bracing or timbering is necessary to maintain control of the overhead material.

Further, no rock or other earthy material is removed from the area under the arch until the entire arch is completed. In order to protect the concrete arch from damage while shooting out or blasting the underlying structure in the excavation of the tunnel area it is desirable to provide a layer of collapsible material 20 between the concrete arch sections and the underlying rock prior to formation of the sections. Thus, when the entire arch is completed there is a continuous layer of collapsible material lying between the arch and the earth support. Prior to excavating the earth support the collapsible material is broken and removed thus forming a kerf or open space below the green concrete forming the arch, which space will prevent damage to the concrete during excavation. A convenient form of collapsible material has been found to be second grade hollow tile which may be readily broken and removed by hand, but it is understood that any other suitable and available material may be employed.

Excavation of the tunnel area beneath the completed arch may be accomplished in any desired manner, for example by the use of relatively small electric shovels. This excavation is simple and inexpensive due to the great size of the face on which the shovels will be working. As excavation to the desired extent is completed, a coating of cement 18 may be sprayed on the side walls to a thickness determined by local conditions.

The completed structure illustrated in Figs. 1 and 2 may include if desired a lock as indicated at 22 to control the water level within the structure and a railroad 24 may be extended throughout the length of the structure for servicing the ships or other equipment which may be housed therein.

While the invention has herein been described and illustrated with respect to the construction of arched roofs, it will be understood that the same method may be employed for the construction of flat roofs or roofs of any other desired configuration, adjusting the quantity of reinforced concrete as necessary.

I claim:

1. The method of constructing a tunnel which comprises providing a layer of collapsible material on an earth support, forming a roof immediately above said layer of collapsible material, collapsing said material to provide a kerf between the roof and the supporting earth beneath the roof and excavating said earth to form a tunnel.

2. The method of constructing a tunnel which comprises providing a layer of collapsible material in the form of an arch lying upon an earth support, forming an arched roof immediately above said layer of collapsible material, collapsing said material to provide a kerf between the

arched roof and the earth therebeneath and excavating the earth beneath the arched roof to form a tunnel.

3. The method of constructing a tunnel which comprises, providing a layer of collapsible material lying upon an earth support, forming a roof immediately above said layer of collapsible material, collapsing and removing said material from between the roof and the earth beneath the roof to provide a substantially clean kerf between the roof and the earth therebeneath and excavating the earth beneath the roof to form a tunnel.

4. In tunnel construction the improvement which comprises, providing a layer of collapsible material along a transverse section of the tunnel with the collapsible material lying upon an earth support, forming a transverse roof section above said layer of collapsible material, collapsing said material to provide a kerf between the roof section and the earth beneath the roof section, and excavating the earth beneath the roof section to form a tunnel.

5. The method of constructing a tunnel which comprises providing a layer of collapsible material along a transverse section of the tunnel with the collapsible material lying upon an earth support, forming a transverse roof section above the said layer of collapsible material, repeating the aforesaid steps until the desired number of roof sections is completed to form a roof, collapsing said material to provide a kerf between the roof and the earth beneath the roof and excavating the earth beneath the roof to form a tunnel.

6. The method of constructing a tunnel which comprises forming a plurality of spaced passageways longitudinally of the tunnel, excavating a transverse section of the tunnel area communicating with said passageways to provide space for a roof section, removing the thus excavated material through one of said longitudinal passageways, introducing roof forming materials through another of said passageways and constructing a transverse roof section in at least a portion of the excavated area, repeating said steps until the desired number of roof sections is completed and then excavating beneath the roof to form a tunnel.

7. In tunnel construction the improvement which comprises, forming a plurality of spaced passageways longitudinally of the tunnel, excavating a transverse section of the tunnel area communicating with said passageways to provide space for a roof section and removing the excavated material through one of said longitudinal passageways, introducing roof forming material through another of said passageways and constructing a transverse roof section in at least a portion of the excavated area and then excavating beneath the roof section to form the underlying tunnel area.

8. The method of constructing a tunnel which comprises, forming a plurality of spaced passageways longitudinally of the tunnel, excavating a transverse section of the tunnel area communicating with said passageways at a point remote from the open end of said passageways to provide space for a roof section, removing the thus excavated material through one of said longitudinal passageways, introducing roof forming material through another of said passageways and constructing a transverse roof section in at least a portion of the excavated area, repeating said steps working toward the open end of said passageways until the desired number of roof sections is completed to

form a roof and then excavating beneath the roof to form a tunnel.

9. The method of constructing an underground concrete wall which comprises, forming a plurality of spaced passageways longitudinally of the wall, excavating a transverse section of the wall area communicating with said passageways at a point remote from the open end of said passageways to provide space for a wall section, removing the excavated material through one of said longitudinal passageways, introducing concrete wall forming materials through another of said passageways and constructing a transverse wall section in at least a portion of the excavated area and repeating said excavating, material removal and introduction steps until the desired number of sections is completed to form a wall.

10. The method of constructing a tunnel which comprises, forming a plurality of spaced passageways longitudinally of the tunnel, excavating a transverse section of the tunnel area communicating with said passageways to provide space for a roof section, removing the excavated material through one of said longitudinal passageways, introducing collapsible material and roof forming material through another of said passageways and placing a layer of collapsible material in the lower portion of said space and forming a roof section in the upper portion of said space upon said layer of collapsible material, repeating the said excavating and material removal and introduction steps until the desired number of roof sections is completed and a substantially continuous layer of collapsible material lies between the roof sections and the underlying earth, and then excavating the underlying earth to form a tunnel.

11. In tunnel construction the improvement which comprises, forming a plurality of spaced passageways longitudinally of the tunnel, excavating a transverse section of the tunnel area communicating with said passageways to provide space for a roof section, removing the excavated material through one of said longitudinal passageways, introducing collapsible material and roof forming material through another of said passageways, and placing a layer of collapsible material in the lower portion of said space and forming a roof section in the upper portion of said space upon said layer of collapsible material, collapsing and removing said collapsible material from between the roof section and underlying earth to provide a substantially clean kerf between the roof section and the underlying earth, and then excavating the underlying earth to form the underlying tunnel area.

12. In tunnel construction the improvement which comprises, forming a plurality of spaced passageways longitudinally of the tunnel, excavating a transverse section of the tunnel area communicating with said passageways at a point remote from the open end of said passageways to provide space for a roof section, removing the excavated material through one of said longitudinal passageways, introducing collapsible material and roof forming material through another of said passageways and placing a layer of collapsible material in the lower portion of said space and constructing a transverse roof section in the upper portion of said space upon said layer of collapsible material, collapsing said layer of collapsible material to provide a kerf between the roof section and the underlying earth and then

excavating the underlying earth to form the underlying tunnel area.

13. The method of forming a tunnel closed at one end which comprises driving a plurality of spaced passageways from the open end of the tunnel longitudinally of the full length of the tunnel to provide outer passageways one at each lateral edge of the tunnel roof area and a passageway intermediate said edges, excavating successive transverse sections of the tunnel area beginning at the closed end thereof across said passageways to provide space for a layer of collapsible material and roof sections, removing the excavated material through said outer passageways, introducing collapsible and concrete roof forming materials through said intermediate passageway after selected transverse sections are excavated and placing a layer of collapsible material in the lower portion of the selected excavated section and forming a concrete roof section in the upper portion thereof above said layer of collapsible material, the concrete roof sections and underlying layer of collapsible material being continuous throughout the length of the tunnel, removing said layer of collapsible material to provide a kerf between the tunnel roof and the unexcavated material therebeneath and then completing excavation of the tunnel area to form the tunnel.
14. The method of forming an underground tunneled dry dock which comprises driving a plurality of spaced passageways from the forward end longitudinally of the full length of the dry dock tunnel to provide outer passageways one at each lateral edge of the tunnel roof area and a passageway intermediate said edges, excavating successive transverse sections of the tunnel roof area across said passageways beginning at the rearward end thereof and working toward the forward end to provide space for roof sections, removing the excavated material through said outer passageways, introducing concrete roof forming material through said intermediate passageway after selected transverse sections are excavated and forming a concrete roof section in at least a portion of the selected excavated section, the concrete roof sections thus formed being substantially continuous throughout the length of the dry dock tunnel, then excavating the earth underlying the roof sections to complete formation of the tunneled dry dock area and finally applying a coating of cementitious material to the side walls of the tunnel.
15. The method of forming an underground tunneled dry dock which comprises driving a plurality of spaced passageways from the forward end longitudinally of the full length of the dry dock tunnel to provide outer passageways one at each lateral edge of the tunnel roof area and a passageway intermediate said edges, excavating successive transverse sections of the tunnel roof area across said passageways beginning at the rearward end thereof and working toward the forward end to provide space for a layer of collapsible material and roof sections, removing the excavated material through said outer passageways, introducing collapsible and concrete roof forming materials through said intermediate passageway after selected transverse sections are excavated and forming a layer of collapsible material in the lower portion of the selected excavated section and a concrete roof section in the upper portion thereof between said roof section and the unexcavated supporting material com-

prising the remainder of the tunnel area, the concrete roof sections and underlying layer of collapsible material being substantially continuous throughout the length of the tunnel, removing said layer of collapsible material to provide a kerf between the tunnel roof and the unexcavated material therebeneath, then excavating the material beneath the roof to complete formation of the tunneled dry dock area and finally applying a coating of cementitious material to the side walls of the tunnel.

16. The method of constructing a tunnel which comprises providing a layer of collapsible hollow tile in the form of an arch lying upon an earth support, forming an arched concrete roof immediately above said layer of collapsible hollow tile, collapsing said hollow tile to provide a kerf between the arched concrete roof and the earth there beneath, and excavating the earth beneath said arched concrete roof to provide a tunnel.

17. The method of constructing a tunnel which comprises excavating a transverse underground section of the tunnel area, providing a layer of collapsible hollow tile in the lower portion of said excavated section, forming a concrete roof in said excavated section immediately above said layer of collapsible hollow tile, collapsing said hollow tile to provide a kerf between said concrete roof and the earth there beneath, and then excavating said earth.

18. The method of constructing a tunnel, which comprises: forming an underground passageway of substantially less width than the desired width of the tunnel inwardly from a working face; widening said passageway at the inner end thereof to form a transverse chamber of a width greater than said desired tunnel width and of a height about equal to the desired roof thickness; introducing roof forming material into said chamber to substantially fill the same to provide a transverse roof section of the desired thickness; and then excavating beneath the roof to form a tunnel.

19. The method of constructing a tunnel, which comprises: forming an underground passageway of substantially less width than the desired width

of the tunnel inwardly from a working face; widening said passageway at the inner end thereof to form a transversely arched chamber of a width greater than said desired tunnel width and of a height about equal to the desired roof thickness; introducing roof forming material into said chamber to substantially fill the same to provide a transversely arched roof section of the desired thickness; and then excavating beneath the arched roof to form a tunnel.

20. The method of constructing a tunnel, which comprises: forming underground passage means of substantially less width than the desired width of the tunnel inwardly from a working face; widening said passage means at the inner end thereof to form a transverse chamber of a width greater than said desired tunnel width and of a height about equal to the desired roof thickness; introducing roof forming material into said chamber to provide a transverse roof section of the desired thickness; successively forming similar transverse chambers working toward the outer end of said passage means and successively introducing roofing material into said chambers to form successive roof sections until the entire roof is completed; and then excavating beneath said roof to form a tunnel.

21. The method of constructing a tunnel, which comprises: forming underground passage means of substantially less width than the desired width of the tunnel inwardly from a working face; widening said passage means at the inner end thereof to form a transverse arcuate chamber of a width greater than said desired tunnel width and of a height about equal to the desired roof thickness; introducing roof forming material into said chamber to provide an arched roof section of the desired thickness; successively forming similar transverse chambers working toward the outer end of said passage means and successively introducing roofing material into said chambers to form adjoining arched roof sections until the entire roof is completed; and then excavating beneath the arched roof to form a tunnel.
